UNITED STATES PATENT OFFICE.

JACOB WATSON, OF YONKERS, NEW YORK, ASSIGNOR TO M. J. WHITTALL, OF WORCESTER, MASSACHUSETTS.

DESIGN FOR A RUG.

SPECIFICATION forming part of Design No. 19,542, dated December 31, 1889.

Application filed December 5, 1889. Serial No. 332,730. Term of patent 3½ years.

To all whom it may concern:

Be it known that I, JACOB WATSON, residing at Yonkers, county of Westchester, State of New York, have invented and produced a new and original Design for a Pattern to be Wrought into Wilton Rugs and other Carpeting, in such colorings as may be designed; and I do hereby declare that the photographic illustration accompanying this specification gives and conveys to any one skilled in the art of carpet weaving and manufacture a clear understanding of the same, and is sufficient to enable such person to use my invention.

What I claim as my invention, and desire to secure by Letters Patent, is—

The design for rugs, substantially as shown in the photographic illustration accompanying this specification.

JACOB WATSON.
